(57) **CLAIM**

The ornamental design for a decorative hanger for a shower curtain or fan, as shown and described.

DESCRIPTION

FIG. 1 is a front view showing my new design;

FIG. 2 is a left view thereof;

FIG. 3 is a back view thereof;

FIG. 4 is a right view thereof;

FIG. 5 is a top view thereof; and

FIG. 6 is a bottom view thereof; and,
FIG. 7 is a perspective view showing my design on a shower curtain.

The broken lines showing the curtain rod, curtain and additional ornaments in FIG. 7 are for illustrative purposes only and form no part of the claimed design.
